UNITED STATES PATENT OFFICE

EDWARD THOMPSON MORRISS, OF LETCHWORTH, ENGLAND

PERAMBULATOR AND THE LIKE

Application filed February 26, 1925, Serial No. 11,843, and in Great Britain August 20, 1924.

This invention relates to perambulators and to similar vehicles.

The invention has among its objects, while avoiding the necessary use of a separate carrying frame or chassis, to mount the body elastically, to render the vehicle self-steering, and to provide a simple, durable and inexpensive construction.

According to the invention, the axles are carried within massive bearing blocks of an elastic substance, such as spongy vulcanized india-rubber, in such manner that while the axles under road shock are adapted to move vertically and horizontally against the elastic resistance of the bearing blocks, the axles may adapt themselves in position under pressure from the handle-bar, whereby the vehicle is rendered self-steering, in a manner similar to a bath-chair having a loosely pivoted front wheel. Thus the body is elastically mounted upon the axles, so that a substantial amount of play vertically and horizontally is permitted to the axles under the elastic resistance of the bearing blocks.

The bearing blocks may be suitably secured in pairs one on each side within the body, whereby the axles thus pass directly through the body, and the body is thus mounted upon the axles without any separate carrying frame or chassis.

The invention comprises the features which are hereinafter described.

The invention is illustrated by way of example in the accompanying drawings in which

Figure 1 is a side view of a perambulator constructed according to the invention, one of the wheels of which is shown removed.

Figure 2 is an end view, partly in section, corresponding to Figure 1.

Figure 3 is a detail view, partly in section, showing a massive elastic bearing block in position, and Figure 4 shows a corresponding side view of the bearing block separately.

Figure 5 is a sectional side elevation of a constructional modification and Figure 6 is a corresponding detail side elevation corresponding thereto.

In carrying the invention into effect according to one modification illustrated in Fig-

ures 1, 2, 3 and 4, I provide a perambulator body *a*, constructed from three-ply wood or other suitable material of construction, and at or near each end of the side walls of the body near the bottom I provide a pair of oppositely disposed holes or apertures through which the respective axles *c* may transversely pass. These holes or apertures may be circular in shape or they may be of any other suitable shape such as illustrated, and of such ample dimensions as to permit of the play of the axle in the manner described. Adjacent each of these respective holes or apertures a block *d* of elastic substance of the character of india-rubber is mounted, and each of the blocks is advantageously provided with an outwardly protruding part *d*¹ which is adapted on the block being set into position, to protrude externally through the respective hole or aperture.

The bearing blocks are set in position in alignment in pairs and the bearing blocks may be of such dimensions as to rest on the bottom *a*¹ of the body *a*. I have found bearing blocks *d* of the shape illustrated in Figures 3 and 4, made of vulcanized spongy india-rubber of good quality, of 2½ inches high, 2 inches broad and 1½ inches wide, with a transverse hole for the axle near the lower end of each block, to give good results for a perambulator of a standard size, the hole being advantageously so disposed that when the bearing block is set in position, the hole for the axle lies below the middle of the adjacent larger aperture or hole in the side wall as indicated in Figures 1 to 4.

Each of the bearing blocks *d* may be secured or enclosed in position on the body by suitable means, as, for example, by a substantially U-shaped fitting *e*. This fitting *e* may correspond generally in shape with the shape of the block *d* and may be suitably and firmly secured to the side wall and the bottom of the body to enclose or to confine the block, and this may be effected in the use of wood screws or in any other effective way; and on the side opposite that facing the adjacent side wall the fitting *e* may be provided with an inwardly diverted flange indicated in Figure 2 by dotted lines at *e*¹, but any other suitable

means may be provided to secure the respective blocks in position adjacent the respective holes or apertures in the body.

Any suitable means may be provided to ensure against rotation and axial displacement of the axles *c*. For example, the centre part of the axle in position between the pair of blocks *d* may have mounted upon it a tubular sleeve *f*, advantageously formed with a flange *f*¹ at its respective ends bearing upon the inner face of the respective blocks *d*, and this tubular sleeve *f* may be secured in position upon the axle *c* by such means as a cotter pin *g*.

As illustrated in Figures 1 to 3 margin strips *h* of ply-wood, metal or other material may be applied at the respective side walls of the body *a* by means of nails and screws or otherwise, in position adjacent the apertures provided in the side walls for the reception of the elastic blocks *d*, the strips *h* being of a shape corresponding to the apertures, and having their inner edges extending inwardly to form an aperture of slightly restricted height and width for the reception of the outwardly protruding part *d*¹ of the respective block *d*. By such means each of the blocks *c* while being held in position on the inner side by means of the flange *e*¹ or by the sleeve *f* or otherwise, is held at the outer side by the inwardly extending edge of the strip *h*.

Between the respective road wheels *i*, mounted at the outwardly protruding ends of the axle *c*, and the respective adjacent elastic bearing blocks *d*, a short sleeve *j* may be interposed as illustrated in Figure 2. The ends of the respective axles *c* may be screw-threaded or otherwise provided for the reception of a nut *k* or other means for retaining the road wheels *i* in position upon the axle.

The handle *b* may be secured to the body at one end in any convenient way such as illustrated in Figures 1 and 2.

It will be understood that the bearing blocks *d* may be provided of any suitable form and dimensions, and that instead of being provided as massive blocks of spongy or other india-rubber they may be provided with cavities and that such blocks may be adapted to be filled with air under pressure; that the bearing blocks may be secured in position by any suitable means, that instead of being mounted within the body *a* they may be mounted exterior to or beneath the body, and that instead of being provided as single integral blocks they may be provided of different substances, for example, they may be provided with separate sleeves or bushes through which the axle passes, the sleeve or bush being of a different substance to that of the main part of the bearing block through which it passes; or they may be provided of composite layers or parts.

It will furthermore be understood that any

other means than described may be used for preventing the rotation and axial displacement of the axles *c* with reference to the body and the bearing blocks. For example, recesses of a square or other non-circular shape may be provided at the inner faces of the respective bearing blocks *d* in such position that bosses or collars of square or other non-circular shape upon the axle may enter, whereby the axle is thus held against rotation by the bearing blocks. It will moreover be understood that the axles may be provided of any desired and suitable solid or tubular cross-section, and that they may be provided with cranked ends, or in one piece or in connected lengths, but that it is preferred, as illustrated, to provide the axles of solid straight rods of circular cross-section; and that the axles may be formed with or have mounted upon them, at the positions at which they traverse the bearing blocks, a boss or enlargement that may be conveniently of a cylindrical or other shape, the dimensions of the bearing blocks and the form of the holes therein being modified in such a case, so as by such means to accommodate the boss or enlargement referred to and to ensure effective elastic resistance against the play or movement of the axle in the manner described.

As illustrated in Figures 1 and 2, the body *a* of the perambulator is provided with an inwardly protruding ledge *m* or flange on the inside, and this ledge is horizontally disposed and may extend round the body on the inside or as illustrated the ledges are disposed at opposite sides only. The respective seats *n* at the ends may be upholstered and provided of a shape corresponding to the shape of the body at the ends, and each seat *n* is conveniently provided beneath with four blocks or buffers *o*, two at the rear and two in front, or any other number may be employed, the blocks or buffers *o* being so disposed and of such dimensions that they are supported on the ledge referred to.

The blocks or buffers *o* may be provided of vulcanized spongy rubber as the massive bearing blocks, but they are preferably provided of such spongy rubber on the inside and of ordinary solid rubber on the outside.

At the upper part each buffer or block *o* is provided with an integral stud or projecting part *o*¹ connected to the main part of the block *o* by a narrow neck. The buffers or blocks *o* are thus adapted so that they may be secured to the seat *n* by causing the studs or projecting parts *o*¹ to pass through holes provided for their reception in the seat, each stud being thrust through the narrower hole in the seat and extending out on its protrusion, whereby the studs are in a simple or effective way secured or retained in position beneath the seat *n*.

It will be understood that by the provision of the seats *n* at the respective ends a central

space is available, but another seat n^1 similarly provided beneath with buffers or blocks o may be similarly supported on the oppositely disposed lateral ledges m , whereby the perambulator is adapted for the accommodation of an infant in a lying posture. Furthermore, the seats are loosely mounted and thus one or a number may be used according to requirements.

10 In carrying the invention into effect according to the modifications illustrated in Figures 5 and 6, the axles c at the positions at which they traverse the bearing blocks d , have sleeves p mounted therein, and a washer q mounted upon each of the sleeves in position beside the inner face of the bearing block d ; and each washer is maintained in position by means of a cotter pin q^1 . By such means the axles are in a simple way held from axial displacement. The respective ends of the axles c are advantageously reduced and a collar r may be applied at each end in positions between the outwardly protruding end of the sleeve p and the inner end of the hub 25 of the wheels i .

In the construction illustrated in Figures 5 and 6, each of the fittings e by which the bearing block d is held in position, is provided at its upper part with an inwardly extending flange e^1 at its upper part and with outwardly extending flanges e^2 at its lower part, which engage beneath a pair of vertical members s fixedly secured at their ends to the bottom a^1 of the body and the ledge m . By such means the block is simply and securely mounted in position within the body.

30 In the construction illustrated in Figures 5 and 6, simple means are indicated for preventing the rotation of the axles c , consisting of a single rod t bent at its respective ends and passing through diametric holes provided in alignment in the respective axles.

I claim:

1. In perambulators and similar vehicles in combination, a body in whose side walls apertures are provided in opposite position in pairs, massive elastic bearing blocks within the said body adapted to absorb road shock, means for mounting said bearing blocks in positions adjacent to the said apertures, wheel axles passing through said bearing blocks, the said wheel axles being independently movable under road shock; and means for preventing the rotation of the said axles comprising a rod passing in a middle position transversely through the respective axles, substantially as described.

2. In perambulators and similar vehicles in combination the body in whose side walls two pairs of apertures are provided in opposite positions, two pairs of massive elastic bearing blocks within the said body of a substance and form by which the said blocks are adapted to yield to a considerable extent within the limit of elasticity of the said substance on

vertical movement of the road wheels and axles under road shock, the said bearing blocks having holes passing transversely therethrough in positions determined to yield a substantial dimension of the said blocks in the line of support of the load, means by which the said bearing blocks are mounted and secured within the said body in opposite and coincident positions respectively adjacent to the said apertures, and two wheel axles passing through the said body and respectively through the massive elastic bearing blocks of each pair, the said wheel axles being independently movable under road shock to the extent permitted by the substance of which the said bearing blocks are formed and by the dimensions of the said bearing blocks in the line of support of the load by the said axles, substantially as hereinbefore described.

3. In perambulators and similar vehicles in combination the body in whose side walls two pairs of apertures are provided in opposite positions, two pairs of massive elastic bearing blocks within the said body of a substance and form by which the said blocks are adapted to yield to a considerable extent within the limit of elasticity of the said substance on vertical movement of the road wheels and axles under road shock, the said bearing blocks having holes passing transversely therethrough in positions determined to yield a substantial dimension of the said blocks in the line of support of the load, means by which the said bearing blocks are mounted and secured within the said body in opposite and coincident positions respectively adjacent to the said apertures and two wheel axles passing through the said body and respectively through the massive elastic bearing blocks of each pair, the said wheel axles being independently movable under road shock to the extent permitted by the substance of which the said bearing blocks are formed and by the dimensions of the said bearing blocks in the line of support of the load by the said axles, substantially as described.

EDWARD THOMPSON MORRISS.
